UNITED STATES PATENT OFFICE.

WILLIAM B. LOVATT, OF WEATHERLY, DENNIS A. REHRIG, OF MAHONING TOWNSHIP, CARBON COUNTY, AND PIERCE F. REHRIG, OF LEHIGHTON, PENNSYLVANIA.

ATTACHMENT FOR QUILLING-MACHINES.

953,914.

Specification of Letters Patent.

Patented Apr. 5, 1910.

Application filed May 24, 1909. Serial No. 497,952.

To all whom it may concern:

Be it known that we, WILLIAM B. LOVATT, residing at Weatherly, Carbon county, Pennsylvania; DENNIS A. REHRIG, residing at Mahoning township, Carbon county, Pennsylvania, and PIERCE F. REHRIG, residing at Lehighton, Carbon county, Pennsylvania, have invented a certain new and Improved Attachment for Quilling-Machines, of which 10 the following is a specification.

Our invention is an attachment for any style of quilling machine where tension or drag is required for the spooling or quilling of silk, cotton, wool or other material.

15 Our invention has for its object to provide an attachment which may be placed upon any style of quilling machine and over which the thread is passed in its travel from the bobbins or swifts to the quills or bobbins 20 on the take-up spindles and which can be so adjusted that the desired degree of "drag" on the thread may be maintained.

Our invention also has for its object to provide means whereby loose ends or waste 25 of thread or broken strands may be gathered and prevented from passing to the quills along with the thread proper.

Our invention also resides in those novel 30 details of construction, combination and arrangement of parts all of which will be first described, then be specifically pointed out in the appended claims and illustrated in the accompanying drawings, in which:

Figure 1, is a perspective view of a part of 35 a quilling machine illustrating the application of our invention. Fig. 2, is a detail view of the roll. Fig. 3, is a cross section on the line 3-3 of Fig. 2. Fig. 4, is a similar view illustrating a modified form of 40 roll. Fig. 5, is a horizontal section on the line 5-5 of Fig. 6. Fig. 6, is a section on the line 6-6 of Fig. 5. Fig. 7, is a detail view illustrating the passage of a thread through the forked or slotted member. Fig. 45 8, is a detail view of a modification of the invention.

Referring now to the accompanying drawings in which like letters and numerals of reference indicate like parts in all of the 50 figures, 1 designates the quilling machine which is provided with the usual brackets 1^a and top bar 1^c. To the brackets 1^a are fastened by adjustable clips 3^a, standards 3 which have bearings 4 to receive the ends 5^a 55 of a roll 5, the bearings 4 being clamped by

bolts 4^a or in any other approved manner to hold the roll 5 stationary. The roll 5 is covered with plush 6, or other suitable material. Blocks 7 are secured to the roll 5 at desired intervals and the blocks 7 are provided with slots 7^a, the slotted surfaces of the blocks being covered with plush 8, or other suitable material. The blocks 7 are secured to the rolls 5 by screws 9 or in any other desired manner. 60

10 represents bobbins which are held either on vertical spindles 11 or in a horizontal position by supports 12 on a rod 1^d of the quilling frame. From these bobbins 10 the thread 15 is passed around or over 70 adjusting rods 2 of glass or other suitable material, after which the thread is passed over the roll 6 and through one of the slots 7^a to the quills or bobbins 10. Instead of taking the thread from bobbins 10 the thread 75 may be taken from a swift 13 supported on the bar 1^c or supports 14, as indicated, or the swifts may be supported in any other desired way. The rods 2 are carried by clips 2^a which are adjustable in the brackets 1^a so 80 that they may be shifted along the brackets to bring the thread 15 into greater or less contact with the roll surfaces as conditions may require and thus increase or decrease the drag as desired. The contact of the 85 thread 15 with the roll surface 6 may be also adjusted or varied by making the roll 5 of oval or other similar cross sectional shape, as shown in Fig. 4, of the drawings, and by turning the roll of Fig. 4 on its axis a 90 greater or less tension on the thread 15 may be had.

By passing the thread 15 through the slots of the member 7, any loose particles of thread will be prevented from passing 95 through the slot, as shown in Fig. 7, to the quills or bobbins on the take-up spindles of the quilling machines. The thread which passes to the quills will be cleaned, as it were; furthermore, by providing the slotted 100 member 7 for the thread to pass through should the thread consist of more than a single strand of material and one or more of such strands become dropped from the full thread then the slotted member 7 will 105 act as a catcher or preventer and hold or break the thread and thereby prevent imperfect threads from passing onto the quill, bobbin or spindle.

In Fig. 8 is disclosed a slight modification 110

of the invention wherein the block 7 is formed of a resilient spring-like member 20 covered with plush 8, or the like, so as to more readily grip the thread 15 to break 5 the thread or hold it tight.

When we speak of the roll 5 being covered with "plush" we desire it understood that any other soft fibrous material may be used in lieu thereof, such for instance as velvet 10 or the like.

We deem it well to call attention to the fact that by the use of this invention quilling machines may be run at a very much greater speed than under the present system 15 of handling material, thereby reducing the cost of production, etc.

Numerous slight changes in the details of construction and arrangement of parts may be made without departing from the spirit 20 of the invention or the scope of the appended claims.

What we claim is:

1. An attachment for quilling machines comprising a plush covered roll over which 25 the thread passes in its travel from the bobbin to the quill, a plurality of rods extending substantially parallel with said roll and spaced apart over which the thread may be passed to vary the amount of contact between 30 the thread and said roll by causing a larger or smaller length of said thread to be brought into contact with said roll and a support for said roll and rods.

2. An attachment for quilling machines 35 comprising a rotatably mounted plush covered roll over which the thread passes from the bobbin to the quill, means for supporting said roll and clamping it from rotation, and means carried by said roll through which 40 said thread passes to strip the thread of loose strands.

3. An attachment for quilling machines comprising a rotatably mounted plush covered roll over which the thread passes in its 45 travel from the bobbin to the quill, means for adjusting the length of contact of the thread with the roll surface, and means carried by said roll through which said thread passes to strip the thread of loose strands 50 and removable means for holding said roll in a given position from rotation and a support for said roll.

4. An attachment for quilling machines comprising a rotatable plush covered roll 55 over which the thread passes from the bobbin to the quill, removable means for clamping and supporting said roll in its adjusted positions, and radially disposed blocks secured to said roll between which the thread 60 passes.

5. An attachment for quilling machines comprising a rotatably adjustably mounted plush covered roll over which the thread passes in its travel from the bobbin to the quill, means carried by said roll through 65 which said thread passes to strip the thread of loose strands, said last named means comprising slotted blocks between which the thread passes, and a support for said roll.

6. An attachment for quilling machines 70 comprising a rotatably adjustably mounted plush covered roll over which the thread passes in its travel from the bobbin to the quill, means for adjusting the length of contact of the thread with the roll surface, 75 means carried by said roll through which said thread passes to strip the thread of loose strands, said last named means comprising slotted blocks between which the thread passes, and a support for said roll.

7. An attachment for quilling machines comprising a rotatably adjustably mounted plush covered roll over which the thread passes in its travel from the bobbin to the quill, means carried by said roll through 85 which said thread passes to strip the thread of loose strands, said last named means comprising plush covered slotted blocks secured to said roll through the slots of which said thread passes, and a support for said roll. 90

8. An attachment for quilling machines comprising a rotatably adjustably mounted plush covered roll over which the thread passes in its travel from the bobbin to the quill, means for adjusting the length of contact of the thread with the roll surface, 95 means carried by said roll through which said thread passes to strip the thread of loose strands, said last named means comprising plush covered slotted blocks secured 100 to said rolls through the slots of which said thread passes, and a support for said roll.

9. An attachment for quilling machines comprising a plush covered roll over which the thread passes in its travel from the bobbin to the quill, a plurality of rods lying in the same plane and spaced apart over which said thread may be passed to vary the amount of contact between said thread and said plush covered roll by causing a larger 110 or smaller length of said thread to be brought into contact with the surface of said roll, and a support for said roll and rods.
